UNITED STATES PATENT OFFICE.

DOMENICO LOMBARDI, OF EAST BOSTON, MASSACHUSETTS.

AUTOMATIC GEM-SETTING MACHINE.

Application filed April 19, 1920. Serial No. 374,895.

To all whom it may concern:

Be it known that I, DOMENICO LOMBARDI, a subject of the King of Italy, and a resident of East Boston, in the county of Suffolk and State of Massachusetts, have invented a new and useful Automatic Gem-Setting Machine, of which the following is a specification, reference being had to the accompanying four sheets of drawings, forming part thereof.

The object of my invention is to provide a simple and reliable machine for setting stones or gems automatically in finger rings, the machine being adapted to operate by hand or power, and particularly applicable for turning out large quantities of the cheaper and less expensive rings.

Other objects and advantages of the invention will more fully appear from the following description thereof.

The invention consists of the novel structural features and combination of elements hereinafter described and particularly pointed out in the claims appended at the foot hereof.

To enable the construction and operation of the invention to be clearly understood by those skilled in the art, reference is had to the accompanying drawings illustrating one of several forms in which the invention may be concretely embodied.

Fig. 1 represents a fragmentary side, elevational view of an apparatus embodying the within invention.

Fig. 2 represents a plan view taken substantially on line 2—2 on Fig. 1;

Fig. 3 represents a fragmentary front elevational view of the apparatus shown in Fig. 1;

Fig. 4 represents a timing diagram of the different functions embodied in the cycle of operations in the within described apparatus;

Fig. 5 represents a sectional view taken substantially on line 5—5 on Fig. 1, but shows the ring plunger in the down position, instead of the raised position shown in said Fig. 1;

Fig. 6 represents a plan view of the apparatus shown in Fig. 1;

Fig. 7 represents a sectional view taken on line 7—7 on Fig. 1;

Fig. 8 represents a sectional view taken substantially on line 8—8 on Fig. 1;

Fig. 9 represents a sectional view taken on line 9—9 on Fig. 1;

Fig. 10 represents an enlarged, fragmentary, sectional and part elevational view of the stone or gem feeding magazine mechanism of the within described apparatus. 60

Fig. 11 represents an enlarged, fragmentary, sectional and part side elevational view of the gem setting and magazine section of the apparatus taken substantially on line 11—11 on Figs. 3 and 10; 65

Fig. 12 represents a sectional view taken on line 12—12 on Fig. 10;

Fig. 13 represents a part of the view shown in Fig. 11, but shows the magazine mechanism in the act of discharging a single 70 stone into the ring with which the same is to be set;

Fig. 14 represents a similar view to that shown in Fig. 13, but shows the magazine mechanism advancing the column of stones 75 therein, and the setting mechanism ready to engage the prong tips of the ring for bending the prongs to set the stone in the ring; and

Fig. 15 represents a plan view of the setting mechanism of the apparatus. 80

The terms employed herein are used in the generic and descriptive sense to designate the elements illustrated, and are therefore not primarily intended as terms of limitation. 85

Like numerals refer to like parts throughout the several views of the drawings.

The numeral 20 represents the main casing of the apparatus which is preferably 90 provided with the upright support 21 in the rear thereof which may be made integral therewith or separate and rigidly secured thereto, according as may be desired. Said casing 20 is preferably provided with 95 suitable bearings for rotatably supporting the drive-shaft 22, the cam-shaft 23, and the turntable-shaft 24, and is further provided with means for supporting the upright stud 25 which rotatably supports the 100 driving mechanism of the intermittent device, as the Geneva gear mechanism shown employed in the drawing, for timing and actuating the turntable-shaft 24.

The upright support 21 is preferably machined to accommodate the reciprocating plunger member 26, which is preferably made square-sectioned, as shown, and slidably mounted in said support 21. Said reciprocating plunger member 26 is preferably provided on its lower end with the cam roller 110 27 which rides in the cam track 28 of the

plate cam 29 and on its upper end with the yoke-stud 30 which carries the floating yoke member 31 with said plunger member 26; said floating yoke member being also 5 slidably mounted in said upright support 21 and normally set adjacent to said plunger member 26 to reciprocate therewith but allowed to lag behind said plunger member, when occasion requires it, by the expansion 10 spring 32 which is provided on the stud 30 for the purpose.

35 represents the magazine bracket which is rigidly mounted on and secured to the top of the upright support 21, as shown 15 (Figs. 1 and 3), and provided with the parallel bearings for rotatably supporting the magazine feed tripper cam shafts 36 and 37, which are respectively provided with the sprockets 38 and 39 in the rear thereof 20 and the cams 40 and 41 at the front thereof; said sprockets and cams being secured to said respective shafts 36 and 37 for rotating therewith. Said bracket 35 is further provided with the vertical magazine 25 bearing 42, which is bored to accommodate the removable magazine tube 43 which is held therein in secured position therewith by means of the winged set screw 44 provided in the bracket 35 for the purpose. 30 Said bracket 35 also provides the supports 45 for the tripper pivot-studs 46 which pivotally support the magazine trippers 47 and 48 on said bracket, and which are actuated, respectively, by the tripper cams 40 and 41 35 and held to frictionally engage therewith by the spring members 49 and 50, respectively.

Said tripper members are each preferably provided with the intermediate, elongated openings 51, as shown in Fig. 11, and with the adjustable bushings 52, which thus permit of adjustment of said tripper members independently and in relation to each other and in relation to the fixed pivot-studs 46, the purposes of which adjustment will be hereinafter more fully explained. Said tripper members 47 and 48 are each provided at the lower ends thereof with the forked fingers 53 and 54, respectively, which project into the magazine tube 43 through slots 55 provided therein for the purpose at the bottom thereof, the forked fingers straddling the stones or gems above the point at the bottom, as indicated in Figs. 10 to 12, inclusive.

60 represents the plier bracket of the machine, which may be made integral with the upright support 21, or separate and rigidly secured thereto to form part thereof; said brackets being provided with a central opening 61 which centers with the magazine tube center, as shown in Fig. 1, and carries secured thereto the cluster of radial plier units comprising the forked brackets 62 which pivotally support the

plier or bell-crank-cam triggers 63 therein, and which triggers 63 are provided with plier points or prong engaging ends 64 which are so shaped, in cam fashion, to yield the function of bending over the 70 prongs P of the ring R and to close said prongs in on the stone S to secure the same in set position with the ring. Said triggers are preferably bevelled off laterally at the plier points, as shown in Fig. 15, to form a 75 complete closure to insure engagement with all of the prongs P of the ring. This complete closure of the plier points will locate the prongs although the same may be slightly out of true, as might sometimes be the 80 case. The actuating ends 65 of said triggers 63 are preferably provided with the end slots or recesses 66, which interlock said actuating ends 65 with the actuating ring 67, which ring in turn is carried by the 85 floating yoke member 31 and is secured thereto to form a part thereof.

The drive-shaft 22 carries therewith the worm-gear 70 (Fig. 1) within the casing 20, and the pulley or drive-wheel 71 outside 90 said casing 20, as shown in Fig. 3. The worm-gear 70 engages with the worm-wheel 72, which, together with the ring chuck cam 73 and the Geneva drive-gear 74 as well as the cam 29, are all mounted on the cam-shaft 23 and are all secured thereto to rotate therewith. The gear 74, which is a bevel-gear, engages with the bevel-gear 75 (Fig. 1) which is mounted on the stud 25 and carries therewith the intermittent 100 drive-wheel 76 of the so-called Geneva stop mechanism; said drive-wheel 76 having the usual locking cam 77 and the shifting pin or roller 78 which engage with the star wheel 79 carried on the 105 turntable upright shaft 24 and secured thereto to rotate therewith. The star wheel 79 is provided with the locking cam sections 80 and the intermediate and radial slots 81, and forms a part of the so-called 110 Geneva intermittent mechanism hereinabove referred to.

85 represents the magazine drive sprocket which drives the magazine tripper cam sprockets 38 and 39 through the endless 115 sprocket chain 86 engaging with same, as indicated in Figs. 1 and 3.

90 represents the turntable of the machine, which in the drawings is shown provided with a set of four ring chucks spaced 120 90° apart from each other. The turntable 90 is mounted on the turntable shaft 24 and is secured thereto to rotate therewith. Said turntable is provided with the chuck bosses 91 which are bored to accommodate the ring chuck plungers 92, which are keyed with said chuck bosses 91 to be held against turning therein but which are nevertheless free to reciprocate therein for the purposes hereinafter more fully described. The plun- 130

gers 92 are preferably forked at the bottom, as shown in Figs. 1 and 3, and are provided with the cam wiper-rollers 93 which engage with the ring chuck cam 73 when set in the 5 operating position in the machine marked "X" in Fig. 1. Said plungers 92 are preferably provided at the top with the flanges 94 which bring up against the turntable 90 when the plungers 92 are in their lowest positions, and are also preferably recessed 10 above the flanges to accommodate the ring engaging clips 95 which are pivoted at 96 and provided with the ring gripping fingers 97 which engage the rings R, as shown in Figs. 1, 3 and 11, and are frictionally held or gripped thereagainst by the springs 98 provided for the purpose. 99 represents the offset ring supporting shoulder provided on each of the ring chucks, which 15 shoulder is provided with the ring centering nipple 100 in the top thereof and which fits the opening in the ring setting; said nipple 100 being positioned to lie on the vertical center line of the magazine and 20 plier mechanisms of the machine when positioned in the "X" or stone setting position of the machine, as indicated in Figs. 1 and 11. 101 represents the actuating end of the clip 95, and 102 represents the expansion 25 spring which is carried on the ring chucks of the turntable 90, and which spring engaging with the plunger collar 103, normally tends to hold said ring chucks in the 30 down position but yields to the lift of the cam 73. 104 represents the casing hood which is shaped to enclose the turntable and ring chuck mechanisms, as shown in Fig. 1, and may be secured to the casing 20 in any 35 suitable manner to form a part thereof.

40 Fig. 4 represents a timing diagram presenting the cycle of operations of the within described machine and indicating the several functions thereof, as will be hereinafter more fully explained.

45 Having thus described the parts of my invention in detail, the manner in which the same may be operated is as follows:

It will be first noted that the turntable 90 50 as designed in the machine herein disclosed is timed, through the medium of the Geneva intermittent mechanism, to intermittently make a quarter of a turn and then to be locked during a period; while on the other hand, during said turning and locking periods of the turntable, the cam wheel 29 and the cam 73 are each allowed to make a complete turn, that is one revolution.

Secondly, the magazine tube 43 is supplied 55 with the column of stones set therein, with the points downward as shown in Figs. 10 and 11. Thirdly, the magazine tripper fingers 47 and 48 are adjusted, through the adjustable pivoting means 52 provided thereon, to support the two bottom stones S substantially adjacent to each other in the 60 forked sections 53 and 54 of said tripper fingers 47 and 48, respectively; the latter tripper finger engaging with the lower stone, and which tripper finger, when operated, discharges said lowest stone and permits it 65 to drop directly within the open prongs P of the ring R, as shown in Figs. 10 and 13, while the former tripper finger 47 supports the column of stones above the lowest stone by engaging with the second or adjacent 70 stone thereto, as shown in said figures; it being noted that the action of the tripper cam 40 against the tripper finger 47, as indicated in Fig. 14, will actuate the tripper finger 47 and thus drop the column of stones 75 on to the forked section 54 of the lower tripper finger 48, as shown in Fig. 14. Thus the function of the set of tripper fingers 47 and 48 is to discharge a single stone at a time 80 from the magazine tube 43, as the lower one, for example, which is accomplished by actuating the finger 48, as occurs when the tripper cam 41 trips the same. Said lower stone, while supported in the tube 43, is relieved 85 from the weight of the column of stones thereabove, by the supporting feature therefor provided, through the medium of the forked section 53 of the upper tripper finger 47 engaging with the second stone, as shown in 90 Fig. 13. With the lower stone thus discharged from the magazine tube 43, as indicated in the latter figure, the forked section 54 of the tripper finger 48 is brought 95 back into supporting position in said magazine tube 43, as shown in Fig. 14, while the upper tripper finger is withdrawn from within the tube 43 to permit the column to drop in the tube; thus bringing the lower stone in the column into set position with the forked section 54 of the lower tripper finger 48. Thereafter the forked section 53 of the upper tripper finger 47 is brought back into position within the tube 43, as indicated in Fig. 10, when 100 the lower stone, as shown there, is supported in the tripper finger 48, while the column of stones above the same in the tube 43 is supported on the tripper finger 47 again. This operation is repeated regularly during the 105 running of the machine, and is timed to deliver a stone S to each ring as the rings in the turntable chucks, which are supported on the offset sections 99 of the plungers 92 and locked by the clips 95 in position with said chucks, reach the setting position which 110 is indicated "X" in Figs. 1 and 11.

115 With the stone feeding mechanism thus described, the machine operates as follows: The turning of the pulley 71, which may be accomplished by hand or by power, according as may be desired, rotates the shaft 22 which carries the worm 70 which drives the worm-wheel 72 and thus carries therewith the sprocket wheel 85, the cam wheels 29 and 73 and the Geneva mechanism, driving 120 125 130

4
gear 74, the latter engaging with the gear 75 which turns the Geneva intermittent drive-wheel 76, which in turn intermittently rotates the turntable through the star wheel 79 through the angle of 90°, the turning direction of the several parts just referred to being indicated by the small arrows shown in Fig. 1, wherein it will be observed that the turntable operates in the clockwise direction, as indicated by the arrow shown in Fig. 6. It will be here noted that the star wheel, and consequently the turntable, remains locked after the quarter turn imparted thereto by the Geneva drive wheel 76 during the remaining three-quarters of a turn to said drive wheel 76.

The operator is preferably stationed in front of the machine in a position which enables him to readily remove the rings 20 from the turntable chucks which come from the setting position of the machine and which rings have the stones already set therein; it being noted that the mere depression of the actuating end 101 of the clip 25 95 against the tension of the spring 98 will permit the ring to be removed from the turntable ring chuck. In the same manner, the blank setting or ring R may be detachably set and coupled in said chuck, as shown in Figs. 1 and 11, previous to being advanced to the "X" position there shown, when the cam 73 will lift the plunger 92 against the action of the plunger expansion springs 102, which will thus bring and support the ring in receiving position in relation to the magazine tube 43 and within the range of the stone setting mechanism of the machine. The ring chuck cam 73 will hold the chuck in the uppermost position, as represented by "X" in Fig. 1, for substantially 180°, as will be understood from a reference to the shape of the cam shown in Fig. 3. With the chuck thus raised, the tripper cam 41 engages with the tripper finger 48 against the action of the spring 50, which results in releasing the lower stone S, as shown in Fig. 13, whereupon said stone S drops into the open setting or prongs P of the ring R supported in the chuck. The tripper finger 48 is then brought back into its supporting position in the magazine tube 43, as shown in Fig. 14, and the other tripper finger 47 then acts by reason of the tripper cam 40 engaging therewith and actuating the same against a spring 49, which results in releasing the forked member 53 from the stones in the magazine tube 43, as shown in Fig. 14, whereupon the column of stones is allowed to drop so that the lower stone thereof engages with the forked section 54 of the tripper finger 48. Thereafter, the tripper finger 47 is brought back into engagement with the stones in the magazine tube 43 and assumes the position as shown in Fig. 10, wherein it supports the

second stone in the tube with the column thereupon.

With the stone S thus set in the prongs P of the ring, as just explained, the next function of the machine is to set the stone in the ring, and consists of bending over the prong tips in relation to the top or face of the stone and engaging said prongs with the stone to secure same within the setting of the ring. This function is accomplished in the following manner: It being remembered that the forked brackets 62 are rigidly secured to be stationary with the stationary and fixed bracket 60, so that the pivot points provided in said forked brackets about which the triggers 63 oscillate are also fixed and stationary, while on the other hand the yoke member 31, which carries the trigger actuating ring 67, is movable, up and down, and thus through its connection with the actuating ends 65 of the trigger members 63, effects an oscillating motion to said trigger members about said fixed and stationary pivot points thereof. Said yoke member 31 is supported in the frame 21, as hereinbefore described, to yield a reciprocating motion, said motion being effected through the coupling of said yoke member 31 with the reciprocating plunger 26 which is actuated by the cam 29 through the engagement 95 of the plunger roller 27 with the cam track 28 thereof.

It will be noted in Fig. 3, where the cam track 28 in said cam 29 is indicated, that a portion of said track is laid out on variable and contracted radii in relation to the center of the cam shaft 23 whereby the plunger 26, together with the yoke member 31 which is coupled therewith, are provided a reciprocating action, which, so far as the yoke member 31 is concerned, results in oscillating the plier triggers 63. So that when said yoke member 31 is in its lower position, as indicated in Figs. 11 and 13, the plying tips 64 are simultaneously brought into engagement with the prongs P of the ring R in a manner which forcibly bend the prong tips over on to the stone, as shown in Fig. 14, and finally clamp them into position with the stone, as shown in Fig. 11, whereby the stone becomes set in the ring; it being understood that all of the plier triggers operate radially, as indicated in Fig. 15, with equal pressure and simultaneously. The up position of the yoke member 31, as indicated by the dotted position shown in Fig. 11, which corresponds to Fig. 13, withdraws the plier tips 64 of the triggers 63 and opens them up as shown in said Fig. 13. It will be here noted that said yoke member 31 is floatably coupled with said plunger member 26 through the medium of the yieldable coupling means carried on said plunger 26, to wit, the coupling stud 30 (Figs. 1 and 11) which is sup-

plied with the expansion spring 32 which acts between the stud head and the floating member 31 for frictionally abutting said floating member 31 with said plunger member 26 in the normal operations thereof. This floating feature is preferably provided in a machine, as herein disclosed, which is designed to work on different sizes of stones. Thus, as will be understood in the case of 10 a deep stone with the floating feature provided, the yoke member 31 will serve as a protection against crushing the stone. The floating yoke will bend the prongs over onto the stone sufficiently to set the stone 15 in the setting of the ring, and will then lag behind the plunger 26 to prevent the crushing of the stone, as might otherwise happen in the case of employing a rigid connection between the cam and the yoke member, as will be understood.

Thus it will be observed that while the ring chuck, which assumes the "X" position, as shown in Fig. 1, is up and provided with the stone S, that thereafter the cam 29 25 draws the plunger 26 with its correlated yoke member 31 downward, thereby affecting the set of trigger members 63 by drawing the plier tips thereof in towards the center of the stone, and consequently bends 30 over the prong tips and sets them with the stone to permanently secure the stone in the setting of the ring. With this operation completed the plunger 26 with the yoke member 31 is caused to travel back up again, which 35 opens up the plier triggers and withdraws them from the ring. Thereafter the ring chuck carrying the completed ring is lowered on the decline provided thereon on the cam 73, and the chuck with the ring thereon is allowed to clear under the fixed bracket 60, as can be noted from Fig. 1. With the chuck thus lowered, the Geneva driving 40 wheel 76 engages the shifting pin or roller 78 thereof with the slot 81 of the star wheel 79 and imparts a quarter turn thereto which carries therewith the turntable 90, and consequently advances the next ring chuck to the "X" position, where the operations of 45 feeding the stone and setting the same in the ring, as herein just described, are again repeated.

The diagram shown in Fig. 4 sets forth the cycle of operations in the machine per revolution of the cam shaft 23, and serves 50 to readily present the functions of the machine in their relative order.

It will be understood that the magazine tube 43 may be made of sufficient length to accommodate a substantial number of stones 55 therein, and that if desired, the same may be readily removed from the magazine bracket by unscrewing the set screw 44 which will free the same and allow the removal thereof from the magazine bracket. 60 This removable feature of the magazine

tube permits of replacing a tube adapted to contain stones of a different size, as may be required; it being understood that by properly shaping the cam tips of the plier triggers, the same set of triggers will operate a 70 variety of sizes of ring settings without adjustment.

It will thus be understood that the machine may be employed for setting stones automatically in finger rings which are fed 75 to the ring chucks which are carried on the turntable and advanced one by one to the setting position, where the ring receives a single stone discharged from the magazine provided in the machine and where the stone 80 is finally set in the ring, after which operation the chuck is advanced by quarter turns and brought around where the operator may remove the finished ring therefrom and replace it with a setting which will pass 85 through the within described cycle of operations and be delivered with the stone set therein.

The mechanism of this device is exceedingly simple, and the operations thereof are 90 positive. The speed may be regulated to suit the requirements of the operator, and various types and sizes of stones may be set in correspondingly various types and sizes of rings. The functions of the machine, with the exception of feeding the ring, are automatic and simple in every respect, so much so that any ordinary person 95 may operate the machine.

The work of the machine in setting the 100 stones is uniform and regular, and thus overcomes the need for accurate and expensive hand labor otherwise required for setting stones in finger rings, especially in the case of the cheaper and less expensive types 105 for which this machine is more particularly intended.

The work of bending over the tips of the ring prongs is relatively light, and by providing plier triggers of hard metal a relatively small degree of pressure against said 110 plier tips will be necessary to accomplish the result herein sought to be obtained.

While I have shown the device herein 115 designed to operate on a set of four ring chucks, it will be understood that by suitably designing and timing the apparatus, a turntable with any suitable number of chucks may be provided, more than the four chucks herein shown, or less, according 120 as may be desired. Also, while I have shown a set of six plier triggers used in the machine, any other number may be employed in a similar manner if so desired.

The parts are simple and comparatively 125 few in number, and as will be understood are absolutely positive in their operations. The machine may be made to work as fast as human hands can receive the finger rings and feed the same thereto; thus providing 130

a machine which is capable of yielding a large output at a very small expense.

While the preferred embodiments of my invention have been described in detail, it will be understood that I do not wish to be limited to the particular construction set forth, since various changes in the form, material, proportions, and arrangement of parts, and in the details of construction may be resorted to without departing from the spirit and scope of the invention, or destroying any of the advantages contained in the same, heretofore described and defined in the subjoined claims.

Having thus described my invention in detail, what I claim as new is:

1. In a device of the character described, a turntable member provided with a plurality of ring chucks, each adapted to carry a ring secured thereto, said turntable being adapted to advance said chucks in consecutive order to the setting position in the device and locking same therein during the setting operation thereof; a magazine supplied with stones adapted to feed a stone to each ring reaching said setting position; and a cluster of prong engaging triggers adapted to simultaneously engage with the prongs of said ring so supplied with the stone for bending the tips of said prongs over the stone to set same securely with said ring.

2. In a device of the character described, a turntable member provided with a circumferential series of duplicate chuck members, each adapted to disengagedly engage a ring therefor; means for advancing each of said chuck members to the stone receiving and setting position in the machine and for locking the turntable in said advanced position; a stone magazine adapted to feed a stone to the ring so advanced to the setting position; and means for yieldably engaging a cluster of plier triggers with the tips of the prongs of the ring for receiving the stone fed thereto by the magazine in set relation in the ring.

3. In a device of the character described, an intermittently operated rotatable member provided with a circumferential series of duplicate ring chucks carried therein and independently operated therein; means for raising the chucks in said rotatable member to the setting position; a stone feeding magazine provided with tripper means adapted to discharge a single stone into each of the rings carried in said ring chucks when the latter are advanced by said rotatable member and raised into the setting position by said chuck raising means; and a cluster of plier levers coupled to operate similarly and simultaneously against the ring prongs for setting and securing the stone in the ring.

4. In a device of the character described,

a magazine member adapted to contain a column of separate stones placed one on top of the other; and magazine tripper fingers provided with transverse and forked stone engaging ends adapted to communicate with the interior of said magazine member in different planes for engaging the bottom stone and the one adjacent thereto, said tripper fingers being adapted to be actuated alternately to discharge the bottom stone and to advance the column of stones to the discharging end of said magazine.

5. In a device of the character described, the combination of ring chucking means adapted to secure a ring in the operative position on said chucking means and to center the ring in the setting position of the device; a magazine mechanism adapted to deposit a stone in the ring setting; and a plurality of radial bell crank prong engaging cams adapted to be closed in against the prong tips for bending the same over onto the stone to secure same in the setting of the ring.

6. In a device of the character described, a ring chuck mechanism adapted to support a ring therein and position the same in the stone receiving and setting position; a magazine member supplied with stones adapted to discharge a single stone at a time from said magazine and into the setting of the ring, when the aforesaid chuck mechanism positions the ring in said stone receiving position; a cluster of radially positioned bell crank prong engaging cams supported on fixed pivots and adapted to close in on the setting of the ring for bending the prong tips over on the stone delivered to the ring for setting the same therein; and an actuating yoke member adapted to engage with each of said cams for simultaneously operating the entire cluster to clear or engage with the prongs of the ring according as the case may be.

7. In a device of the character described, an upright magazine member carrying the supply of stones therein in column fashion and provided with a set of alternately operated tripper fingers adapted to allow the bottom stone to be separated from the others in the column and to be discharged from the magazine thereby; a stationary transverse bracket member having a central opening therein centered with said magazine member and provided with a circumferential series of radial trigger supports projecting from said transverse bracket and each trigger support pivotally supporting therein a lateral bell crank trigger provided with a cam tip on the inner arm of same for engaging with a prong of the ring setting, and a forked end on the outer arm of said bell crank; a reciprocating yoke member encircling said triggers and engaging with the forked sections thereof for interlocking

- therewith to actuate all of the triggers simultaneously; means for actuating said yoke member; a turntable provided with a circumferential series of ring chucks each 5 slidably mounted therein and adapted to be brought into the operating zone of said magazine and stone setting mechanism and to be locked into said delivered position during the operations of the aforesaid mechanisms; means for raising the ring chuck, delivered to the operating zone by said turntable, into the stone receiving and setting position; and means for intermittently locking and angularly rotating said turntable.
- 10 8. In a device of the character described, an upright magazine member carrying the stone supply therein in column fashion and provided with a set of alternately operated tripper fingers adapted to allow the bottom 15 stone to be separated from the others in the column and to be discharged from the magazine thereby; a stationary, transverse bracket member having a central opening therein centered with said magazine member and provided with a circumferential 20 series of radial trigger supports projecting from said transverse bracket and each pivotally supporting therein a lateral bell crank trigger provided with a cam tip on the inner 25 arm of same for engaging with a prong of the ring setting, and a forked end on the outer arm of said bell crank; a reciprocating yoke member encircling said triggers and engaging with the forked sections of 30 said triggers for interlocking with same to actuate all of the triggers simultaneously; means for actuating said yoke member; means for yieldably coupling said yoke member with said actuating means for providing a floating feature to said yoke member; a turntable provided with a circumferential series of ring chucks each 35 slidably 40 mounted in said turntable and adapted to be brought into the operating zone of said magazine and stone setting mechanisms and to be locked into said delivered position during the operations of the aforesaid mechanisms; means for raising the ring chuck, delivered to the operating zone by said turntable, into the stone receiving and setting position; and means for intermittently locking and angularly rotating said turntable.
- 45 9. In a device of the character described, a rotating member provided with a circumferential series of ring chucks slidably mounted in said rotating member and adapted to be carried around with said rotary member to be set by same in the stone feeding and setting position of the device; means for intermittently advancing and locking 50 said rotary member with the advanced ring chuck in the stone feeding and setting position; means for reciprocating said ring chuck so advanced to the stone receiving and setting position for temporarily supporting 55 the ring in close relation to the hereinafter mentioned stone feeding and setting mechanism of the device to be operated on by said mechanism; an automatic stone feeding member adapted to discharge and deposit a stone within the setting of the ring; automatic plier cams adapted to engage with the prongs of the ring setting for bending the same over onto the stone for securing the same in the ring setting; and means for 60 actuating the aforementioned operating elements in their timed relation to perform the functions herein described.
- 65 In testimony whereof, I hereunto affix my signature this sixteenth day of April, 1920.
- DOMENICO LOMBARDI.
- Witnesses:
- CHARLES GRILLO,
SPECIOSO PEDOTO.
